US00D813052S

(12) **United States Design Patent** (10) **Patent No.:** **US D813,052 S**
Engelen et al. (45) **Date of Patent:** **** Mar. 20, 2018**

(54) **CONTAINER**

(71) Applicant: **Monsanto Technology LLC**, St. Louis, MO (US)

(72) Inventors: **Wim Engelen**, Vilvoorde (BE); **Hugo Smid**, Antwerp (BE)

(73) Assignee: **MONSANTO TECHNOLOGY LLC**, St. Louis, MO (US)

(**) Term: **15 Years**

(21) Appl. No.: **29/615,075**

(22) Filed: **Aug. 25, 2017**

Related U.S. Application Data

(62) Division of application No. 29/581,979, filed on Oct. 24, 2016, now Pat. No. Des. 795,701, which is a division of application No. 29/551,448, filed on Jan. 13, 2016, now Pat. No. Des. 773,304, which is a division of application No. 29/449,458, filed on Mar. 15, 2013, now Pat. No. Des. 747,652.

(57) **CLAIM**

The ornamental design for a container, as shown and described.

DESCRIPTION

FIG. 1 is a perspective view of a container in accordance with our new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

(Continued)

The broken lines in the drawings illustrate the portions of the container that form no part of the claim.
